SEALED CONTAINER FOR STORING PARENTERAL AND OTHER SOLUTIONS

Philip G. Ralston, Jr., Buffalo Grove, Ill., assignor to
Baxter Laboratories, Inc., Morton Grove, Ill.

Filed Sept. 20, 1971, Ser. No. 182,290

Term of patent 14 years

Int. Cl. D24—02

U.S. Cl. D83—1 U

FIG. 1 is an elevational view of a sealed bag, showing my new design.

FIG. 2 is an elevational view of the sealed bag, rotated 90° about its longitudinal axis with respect to FIG. 1.

FIG. 3 is a plan view of the top bag.

I claim:

The ornamental design for a sealed container for storing parenteral and other solutions, substantially as shown and described.
